BOBBIN STRIPPER

Harold R. Turner, Greenville, S. C.

Application December 28, 1938, Serial No. 248,025

12 Claims. (Cl. 28—19)

The present invention relates to bobbin strippers, and has as its object the provision of improved means for stripping off the waste yarn left on the bobbins expelled from automatic looms. In particular, the invention aims to provide an improved and simplified machine for stripping such waste yarn from the weft bobbins used in weaving silk and rayon. In stripping these bobbins, the usual procedure of mechanically scraping or cutting the waste yarn from their yarn-bearing portions cannot be employed, as any roughening, scratching, or chipping of the polished or enamelled yarn-bearing surfaces would result in fracture of these delicate yarns during subsequent use of the bobbins in weaving. As heretofore in certain instances, resort is had to the use of jets of compressed air to free the ends of yarn from the wound masses of waste remaining on the respective bobbins, the freed ends being thereafter engaged by rotating unwinding rolls which quickly draw off the rest of the yarn from each bobbin over the tip thereof.

In accordance with the novel features of the invention, the waste bearing bobbins to be stripped are fed continuously through air jets by means of a plurality of fingers preferably traveling in a closed path which engage the head ends of the bobbins to propel the latter along a path and through the air jets in pendent tip downward relation. These fingers do not need to engage the head end of each and every bobbin, as by pushing onward an occasional bobbin in the series those bobbins which precede the one thus engaged are likewise impelled onward each through the push of the bobbin immediately following it. These feeding fingers may be made to travel either in a circular path about a vertical or horizontal axis, as by mounting them on a wheel, or in paths of other shapes, as by mounting them on a belt. Further, in accordance with the invention, the compressed air used to free the ends of yarn is delivered through ports or passages formed directly in the spaced tracks which support the bobbins through engagement with opposite sides of their heads or of the rings on such heads in pendent relation for sliding movement along the path thus defined and thus these jets may be made to impinge on the yarn-bearing barrels of the bobbins clear up to the junction of such barrels with the heads of the bobbins, while these air jets still retain their obliquely downward relation needed to blow the ends downward toward the tips of the bobbins; in prior structures, the necessary diameter of the perforated air pipes always used as combined

conduits and nozzles made it impossible to include the upper zone of the wound mass adjacent the fillet and the head within the course of these jets, so that occasional ends of yarn terminating in this zone and adhering to the wound mass failed to be freed, and thus the bobbin failed to be stripped. Additionally, the jets are in staggered relation along the path of the bobbins.

As a further feature of the invention, the opposed unwinding rolls are made in the form of slatted reels which intersect each other's orbit of rotation, so that an end of yarn entering between them will be positively engaged by the outer surfaces of these rolls without the need for mounting the latter in accurate tangential relation; while the slats of these reels may be clad with brushes, as hitherto, in order to ensure unwinding engagement with the ends of yarn, the reels will preferably be covered with removable cloth sleeves which will present the necessary character of surface to cause the yarns to adhere thereto and also permit of their being easily slipped off endwise from the reels first to get the accumulated waste off of the reels and second to permit easy removal of such waste from the collapsed sleeve.

An additional feature of the invention is a sliding cutter for slitting open the wound mass of waste collecting on the brush-clad reels when the sleeves are not used, this cutter cutting open the wound mass of waste yarn lengthwise of the reels with convenience and dispatch for removal of the waste from the reels.

Other aims of the invention, and the manner of their attainment are as will be made plain hereinafter.

An illustrative embodiment of the invention is shown in the accompanying drawings, in which—

Fig. 1 is a side elevation and Fig. 2 a plan view, of a machine embodying the features of the invention, a portion at midlength being omitted for convenience in illustration.

Fig. 3 is a vertical section on line 3—3 of Fig. 2.

Fig. 4 is a vertical section on line 4—4 of Fig. 2.

Figs. 5 and 6 are details, in side elevation and in plan respectively, of the novel bobbin-feeding fingers when arranged to travel in a circular path to a vertical axis.

Fig. 7 is a detail showing in side elevation the arrangement of the feeding fingers when mounted to travel in a vertical plane on a horizontal axis.

Fig. 8 is a detail in end elevation and partly in section showing the application of the slid-

ing cutter to cooperate with a reel having its periphery formed of brush-clad slats.

Fig. 9 is a view looking obliquely downward in the direction of the arrow in Fig. 8, showing the parts illustrated in such figure.

The machine embodying the invention comprises a pair of tracks 1 disposed in horizontal and parallel relation, each of which is mounted on and supported by one of a pair of frame-members 3 also arranged in spaced and parallel relation and supported by uprights 5 of the frame. The tracks 1 are spaced apart just far enough to engage the heads, or preferably the steel rings 2 on the heads, of bobbins 4 dropped down tip foremost through the space between the opposing rails, so that these bobbins are supported by their head ends in pendent tip downward relation for free sliding movement along the path defined by the two tracks, with the entire yarn-bearing portions or barrels of the bobbins, and the tips as well, free from all contact with parts of the machine.

As heretofore in certain instances, compressed air is blown against the portions of the barrels of the bobbins on which the feeler waste remains, to free the outer end of the yarn from the wound mass and blow it downward, along with a certain portion of the immediately following turns of waste yarn, so that this end just freed may be mechanically engaged and drawn off to strip the bobbin completely. In accordance with the invention, the tracks 1 are provided with transverse air passages 7 to which air is supplied under pressure from any suitable source of compressed air through pipe 9, manifold 11, and laterals 13. These transverse passages terminate in downwardly inclined discharge orifices 15 from which jets of air are discharged obliquely downwardly at an angle of about 60° to the vertical, against the yarn-bearing portions of the bobbins as the latter are slid in pendent relation along the tracks 1. By putting the discharge nozzles 15 right in the tracks 1, it is possible to subject the uppermost end of the barrel of the bobbin and even the fillet itself joining the head and barrel to the action of the air jets while still giving such jets the necessary downward component of travel needed to carry the yarn down over the tip of the bobbin. Thus when the outer end of the wound mass of yarn happens to lie right at the fillet it will not as sometimes heretofore escape being freed and blown downward into range of the mechanical unwinding devices. It is also to be noted that the successive nozzles 15 on opposite sides of the path of the bobbins are arranged in staggered or alternating relation and not directly opposite each other, as indicated by the position of the lateral air pipes 13 in Fig. 2. This results in each bobbin receiving blasts of air from alternating sides as it proceeds along the tracks, an action which has been found more effective in loosening the ends of yarn than where opposing jets are simultaneously directed against the bobbin from opposite sides.

To engage the ends of yarn thus blown down and trailing off from the tip ends of the pendent bobbins, a pair of opposed rolls or reels 16 is employed with their axes horizontal and parallel and their peripheries opposed to each other along a horizontal line in the vertical plane of movement of the bobbin axes, as hitherto. However, as distinct from prior forms, these reels rotate on axes which are spaced apart a distance less than the sum of the radii of the two reels, and

are geared together so that when rotated in the direction of the arrows in Fig. 4 the slats 17 of one reel will intersect the orbit of the corresponding slats of the other reel entering between such slats, thus insuring that any trailing end of yarn dropping between the concurrent surfaces of the two rolls will be brought forcibly into contact with the surfaces of the rolls, without need for the careful setting of the roll surfaces hitherto necessary in order to insure engagement, and, most of all, providing for the increase in the effective diameter of the rolls as the waste yarn accumulates thereon without need to provide special yielding mountings for their shafts in order to prevent jamming or breakage. The slats 17 may be simply clad with brushes as in Figs. 8 and 9, or pile fabric to engage the trailing ends of yarn; but preferably the slats of each reel 16 will be bare and smooth, and over them will be drawn a tube or sleeve 19 of pile fabric such as corduroy, adapted to be slipped off endwise from the reel after it has become loaded with windings of waste yarn, so that a new and unencumbered sleeve may be quickly slipped on to take its place. To provide for this quickly effected clearing of the winding rolls, they are mounted in the frame with capacity for quick and easy unstepping and replacement. Thus, there is a member 20, Fig. 1, at one end 25 of each reel having a reduced extremity 21 which enters the sleeve 23 at one end of each reel 16 and thus supports this end of the reel during its rotation. The member 20 is held in bracket 25 affixed to frame-upright 5 with capacity for endwise withdrawal by handle 27 upon release of thumb screw 29, whereupon the proximate end of reel 16 is released. The other end of each reel is mounted on rotating jack-shaft 31, the reel being driven therefrom by means of engagement 30 of a dog on collar 33 rotating with jack-shaft 31 within a corresponding notch in sleeve 34 fixed on the reel. This arrangement provides for easy unstepping and replacement of this end of the reel also.

In accordance with the invention novel means is provided for feeding a continuous series of bobbins steadily along tracks 1 while subjected during a substantial period of time to the action of the end-freeing blasts and unwinding rolls. This novel feeding mechanism comprises essentially a plurality of feeding fingers, traveling in a closed path, which engage the head ends of the bobbins above the tracks 1, usually making contact with the steel rings on such heads. In the form of Figs. 1 to 6, these fingers 35 travel in a circular path in a horizontal orbit which intersects the path of the bobbin heads as the bobbins are slid along the tracks 1, being pivotally mounted on a rotating support which here comprises a flanged wheel 37 rotatably mounted on a stud 39 fixed in frame-member 3, the flange of wheel 37 being cut away at appropriate spaced intervals as indicated at 41 to permit the fingers 35 to protrude well beyond the rim thereof. The fingers 35 are pivotally mounted on bolts 43 put through the top surface of wheel 37, and each is yieldingly held in radial position against one end of the cut 41 in the flange, by means of expanding coil springs 45 pressing sidewise against the inner end of each finger and supported by abutments 47 within the flange. As shown in Fig. 6, these fingers thus reach into the path of the bobbins sliding along between tracks 1, engaging the head of any bobbin within their range and pushing such bobbin a few inches onward along

the tracks. As the operator of the machine is continuously arranging the bobbins dumped at random into hopper 49 at the feed end of the machine so that they will hang by their heads from the tracks 1, and pushing them along the tracks into range of the fingers 35, the fingers 35 keep advancing one, two or more of the bobbins at the head of the line thus fed to them by hand by an amount equalling the scope of their movement over the space between tracks 1, each bobbin thus propelled transmitting its forward movement to those which have preceded it, while the whole remaining length of the tracks 1 is occupied by a continuous procession of bobbins which is being moved step by step along the tracks and through the air blasts by the push of the following bobbins. In case the procession should become jammed at any point beyond the feeding fingers, the yielding mounting of such fingers permits them to swing far enough out of their normal radial relation to snap by the bobbin heads without damage.

Usually a plurality of these driving units comprising the traveling fingers and their supporting wheels will be distributed along the length of tracks 1, to lighten the load on any one of such units in propelling a lengthy procession of bobbins. In this connection, it is noted that the longer the unwinding rolls and the stretch of track throughout which compressed air jets are administered to the bobbins, the higher the number of bobbins cleaned per minute; for a machine of an over-all length of six feet and an output of ninety bobbins per minute two feeding units such as described are found adequate.

To drive the feeding fingers, a worm gear 51 is fixed to each wheel 37, and is driven by a worm 53 fixed on shaft 55 between bearings 57 on a bracket 59 fixed on frame-member 3.

This shaft 55 is driven through bevel gears 61, 63, Fig. 3, from an upright shaft 65 driven through bevel gears 67, 69, from transverse shaft 71 rotated by V-pulley 73 and V-belt 75 from any suitable or desired source of power (not shown). A second upright shaft 77 is also driven from transverse shaft 71 through bevel gears 79, 81. Bevel pinions 83 on each of the upright shafts 65, 77, drive large bevel gears 85 in opposite directions as indicated by the arrows thereon, these gears 85 being fixed on jack-shafts 31 previously explained as driving the respective winding rolls or reels 16. These shafts and gears are enclosed within gear-case 87, with the exception of gears 61, 63, which have their own housing 89 on top of gear-case 87. A passage for the bobbins is provided through the top center of gear-case 87, a trough-shaped shield 91 being carried through the gear-case to protect the bobbins from thrown oil. Hinged covers (not shown) are commonly provided to enclose and guard the rotating winding rolls 16, a stationary bottom being also provided beneath the rolls to catch falling waste.

To prevent the bobbin heads from riding up away from tracks 1 as they are being propelled onward along the tracks by the push of the following bobbins, a head-guide 93 is suspended over the space between the tracks and slightly above the bobbin heads by means of arches 95 fixed on the tracks at spaced intervals therealong. The extremity of the head guide which is toward the feed end of the machine terminates at the point where the procession of bobbins is first subjected to the push of the first feeding device, namely abreast of the axis of the first

wheel 37; its under surface is beveled off to facilitate entrance of the bobbin heads thereunder.

It has been found desirable in certain instances, as in dealing with bobbins of different types, to mount the wheel 37 carrying the propelling fingers 35 on a horizontal axis as shown in Fig. 7, so that the fingers 35 travel in a vertical orbit located in the plane of the axis of the pendent bobbins as they hang from the tracks 1. This is easily accomplished by mounting the wheel 37 on a transverse shaft 97 and driving the wheel as before by a worm gear and worm

The provisions of the invention for slitting open the wound mass of waste collecting on the reels in using the prior type of unwinding rolls having the slats 17 clad with brushes or bristles instead of employing the sleeves 19 described hereinbefore, is shown in Figs. 8 and 9 in connection with the reel corresponding to the right-hand reel shown in Fig. 4. Actually, one of these cutting devices is provided for each of the two reels, located in corresponding position with respect to each roll. This device slides on a guide-bar 107 mounted on the outward lateral surfaces of uprights 5 by means of brackets 109 bolted to the uprights, the guide-bar extending along and parallel to the periphery of the reel and being mounted in a simple step cut in the proximate surface of gear-case 87. The guide-bar 107 is of rectangular section, mounted with one edge up as shown in Fig. 8, and with the face that is turned away from the reel provided with teeth to form a rack. On this guide-bar slides a carriage 111 fitting closely about three sides of the guide-bar, and having an extension reaching within the orbit of the brush-clad slats 17 of the reel on which is mounted a triangular knife 113 having sharp edges 115 which cooperates with a sharp-edged disk 117 fixed to a pinion 119 rotating freely on a stud 121 in the carriage 111, the pinion meshing with the rack to impart rotation to disk 117 when the carriage is slid along the guide-bar 107 by means of the handle 123 to work the device. The reel to be stripped is positioned so that the waste yarn 125 stretching from one slat 17 to the next adjacent slat enters the angle between the fixed knife 113 and the disk 117 as the carriage is moved the full length of the reel along guide-bar 107, the rack and pinion imparting a rotation to the disk which shears the windings and splits open the entire mass of waste wound on the reel along the line of travel of the sliding cutter, the waste then being easily drawn off laterally from the reel by hand in a bundle. Thereafter the cutter is restored to its idle resting position shown in Fig. 9, beyond the end of the reel at the feed end of the machine. As already indicated, there is a separate cutter for each of the two reels.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but what I do claim is:

1. A bobbin stripper having in combination spaced tracks supporting the bobbins by their head ends in pendent tip downward relation, means unwinding the waste yarn over the tips of the bobbins while thus suspended, and a bob-

bin-propelling element moving along the tracks engaging only one bobbin at a time and through such engagement propelling such bobbin and other preceding bobbins along the tracks for a few inches only and thereafter allowing all bobbins thus propelled to stand still while the yarn is being unwound over the tips of the bobbins.

2. A bobbin stripper having in combination spaced tracks supporting the bobbins by their head ends in pendent tip downward relation, means delivering jets of compressed air against the yarn-bearing portions of the bobbins while thus supported, winding rolls beneath the bobbins engaging and drawing off over the tips of the bobbins the yarns of which the ends are freed by the air jets, and bobbin-propelling means moving along and over the tracks and engaging behind the heads of the bobbins and thus pushing forward the engaged bobbins and also those not directly engaged, through the air-jets and over the winding rolls for a short distance and thereafter allowing such bobbins to come to rest.

3. In a bobbin stripper, in combination, means supporting the waste-bearing bobbins with capacity for unwinding of the waste yarn therefrom, and opposed unwinding rolls engaging and unwinding the waste yarn from the bobbins, each having salient longitudinal portions and intervening portions of lesser radius, the rolls rotating concurrently and with the orbits of the salient portions of the rolls respectively intersecting each other.

4. In a bobbin stripper, in combination, means supporting the waste-bearing bobbins with capacity for unwinding of the waste yarn therefrom, and a winding roll engaging and unwinding the waste yarn from the bobbins, comprising a tubular fabric cover and a longitudinally-slatted skeleton reel having no surfaces between its adjacent slats to support the cover, thus giving such cover a polygonal shape in cross-section.

5. In a bobbin stripper, in combination, means supporting the waste-bearing bobbins with capacity for unwinding of the waste yarn therefrom, and opposed unwinding rolls engaging and unwinding the waste yarn from the bobbins, each roll comprising a longitudinally-slatted reel and a tubular cover thereover stretched in polygonal shape in cross-section by the reel, the rolls rotating concurrently on axes spaced apart less than the sum of the radii of the cooperating rolls.

6. In a bobbin stripper, in combination, means supporting the waste-bearing bobbins with capacity for unwinding of the waste yarn therefrom, and opposed unwinding rolls engaging and unwinding the waste yarn from the bobbins, each roll having its winding surface defined by longitudinal slats intervening between and intersecting the orbit of the slats on the opposing rolls.

7. In a bobbin stripper, the combination with a winding reel winding off from the bobbins and onto its periphery the waste yarn to be removed, of a knife sliding lengthwise of the roll, and guide means outside the roll directing the knife in a path intersecting the windings of waste yarn on the roll.

8. In a bobbin stripper, the combination with a winding reel winding off from the bobbins and onto its periphery the waste yarn to be removed, of a guide member outside of and extending along the surface of the reel, a carriage traveling along the guide member, and opposed shearing members on the carriage traveling one inside and the other outside the windings of waste yarn on the reel as the carriage is moved along the guide member.

9. In a bobbin stripper, the combination with a winding reel winding off from the bobbins and onto its periphery the waste yarn to be removed, of a rack extending along the surface of the reel, a carriage sliding along the rack, a rotating cutter in geared engagement with such rack and rotated upon movement of the carriage along the rack, and a fixed blade entering inside the windings of waste yarn on the reel and against which the windings are cut by the cutter.

10. A bobbin stripper having in combination spaced tracks supporting the bobbins by their head ends in pendent tip downward relation, means unwinding the waste yarn over the tips of the bobbins while thus suspended, a hub rotating about an axis alongside and transverse to the tracks, and fingers projecting from such hub engaging and propelling bobbins along the tracks, such fingers being mounted on the hub with capacity for yielding movement with respect to the hub.

11. A bobbin stripper having in combination spaced tracks supporting the bobbins by their head ends in pendent tip downward relation, means unwinding the waste yarn over the tips of the bobbins while thus suspended, a hub rotating about an axis alongside and transverse to the tracks, and fingers projecting from such hub engaging and propelling bobbins along the tracks, such fingers being mounted on the hub far enough apart to admit a plurality of bobbins at a time between two successive fingers.

12. A bobbin stripper having in combination spaced tracks supporting the bobbins by their head ends in pendent tip downward relation, means unwinding the waste yarn over the tips of the bobbins while thus suspended, a rotating hub with yielding fingers protruding therefrom to engage and propel bobbins along the tracks during such unwinding, and second rotating hub with yielding fingers receiving the bobbins from the first and assuming the propelling function with respect to the bobbins fed to it by the first.

HAROLD R. TURNER.
